CLAIM

The ornamental design for a coin display and business-card holder, as shown and described.

DESCRIPTION

The ornamental design described herein may be manufactured and used by or for the Government of the United States for all governmental purposes without the payment of any royalty.

FIG. 1 is a perspective view of a coin display and business-card holder showing my new design;

FIG. 2 is a front view thereof;

FIG. 3 is a top view thereof;

FIG. 4 is a left side view, the right being a mirror image thereof; and,

FIG. 5 is a rear view thereof.

The bottom view is omitted and forms no part of the claimed design.

The broken lines in the drawings are for illustrative purposes only and form no part of the claimed design.
